Des. 232,458
Patented Aug. 20, 1974

232,458

NOISE-MAKING TOP

George A. Van Vranken, 1407 Oak Grove Ave., Burlingame, Calif. 94010; and James D. Putz, 1219 Alicante Drive, Pacifica, Calif. 94044

Filed Apr. 10, 1973, Ser. No. 349,799

Term of patent 14 years

Int. Cl. D21—01
U.S. Cl. D34—15 AH

FIG. 1.

FIG. 1 is a perspective view of a noise-making top showing our new design;

FIG. 2 is a left-end elevational view;

FIG. 3 is a side elevational view;

FIG. 4 is another side elevational view shown rotated 90° with respect to FIG. 3; and

FIG. 5 is a right-end elevational view.

We claim:

The ornamental design for a noise-making top, substantially as shown and described.
